UNITED STATES PATENT OFFICE.

WARREN FUHRMANN, OF WESTFIELD, NEW JERSEY, AND EDWARD M. SQUAREY, OF TUCKAHOE, NEW YORK, ASSIGNEES, BY MESNE ASSIGNMENTS, TO WILKINSON BROTHERS AND COMPANY, INCORPORATED, OF NEW YORK, N. Y., A CORPORATION OF NEW YORK.

CROSS-LOCK FOR CALCULATOR SPECIAL KEYS.

1,293,750.

Specification of Letters Patent.

Patented Feb. 11, 1919.

Application filed June 18, 1917. Serial No. 175,279.

To all whom it may concern:

Be it known that we, WARREN FUHRMANN, a citizen of the United States, and a resident of Westfield, in the county of Union and State of New Jersey, and EDWARD M. SQUAREY, a subject of the King of Great Britain, and a resident of Tuckahoe, county of Westchester, and State of New York, have invented certain new and useful Improvements in Cross-Locks for Calculator Special Keys, of which the following is a specification.

The object of this invention is to provide an improved means for preventing operation of a machine by the normal operating means, during the act of depressing or actuating a member that is to cause a special operation of the machine, until the member is depressed to the limit of its movement.

The present invention is especially designed for use with the total or sub-total keys in a calculating machine, whereby the handle or main shaft is locked at once on depression of either key stem, and is not released until the key stem has been depressed the full or proper distance.

This invention is particularly applicable to the total and sub-total mechanism as set forth in U. S. Patent, Serial No. 1,232,007, wherein the depression of the total or the sub-total key serves to move a lever and swing a rock shaft.

In the accompanying drawing showing one embodiment of my invention, Figure 1 is a plan view. Fig. 2 is a side elevation. Fig. 3 is the same view with the parts advanced. Fig. 4 is a partial bottom plan, and Figs. 5 and 6 show the key controlling means.

As shown in the drawings 6 represents the right hand side plate, and 7 the left hand side plate, of the machine. A shaft 8 carries the handle 9, and also a segment 10, on which is a fixed stud 12. A lock arm 13 is pivoted on a stud 14 on the side plate and drawn by spring 15 to cause its hook extremity 16 to engage back of the stud 12 on the segment, to retain the segment in normal position and prevent its being advanced by the handle, as indicated in Fig. 3. A stop arm 17 is fast on a cross shaft 18 that on the opposite side of the machine is secured to a lever 19. This lever carries a

short arm 20 provided with a pin 21 that is engaged by a key stem 22 that is indicated in Fig. 5. A second key stem 23 also engages the pin 21 when depressed. Upon depression of either of these key stems the lever 19 will swing to rock the shaft 18, and swing the stop arm 17. On the lock arm 13 is secured a stud 24 that is engaged by the stop arm 17 in its normal position, see Fig. 2, whereby to hold the hook portion 16 away from the stud 12 against the tension of the spring 15. This will free the stud 12 and permit rocking of the segment 10. But when either of the said key stems is depressed the lock arm 17 will swing downward away from the stud 24, and the spring 15 will swing the stop arm to engage the stud 12 and lock the segment against movement. Upon full swinging of the lock arm 17, it will strike a lug 25 on a bent lever 26 whose upright arm 27 projects into a slot 28 in the stop arm 13. The final downward movement of the lock arm will thus swing the lever 26, whose arm 27 will rock the arm 13, to move its hook end out of engagement with the stud 12 on the segment. A bent lever or pawl 29 is pivoted at 30 and has its recessed end 30^a engaging the stud 24 on the stop arm and is swung to this position by a spring 33 extending between the arm 31 of the pawl, and the arm 27 of the said lever. This pawl will be brought to engage the stud 24 and serve to lock the stop arm in the position free from the stud 12. The parts will remain in these positions during the return of the arm 17, that is usually not returned until the keys 22 and 23 are retracted at the latter portion of the operation of the machine. After the arm 17 is returned to normal position, and swung upwardly its extremity will first strike a stud 32 on the pawl 29, that will swing the pawl back away from the stud 24 and retain it in such position. But at this time the arm 17 will also strike the stud 24 and thus serve to hold the stop arm 13 in the position shown in Fig. 1 free from the stud 12 on the segment. This returns the parts to normal position. It will be understood that when the arm 17 first swings downward the arm 13 will be drawn to engage the stud 12 and the stud 24 on the stop arm will move down free from the pawl 29, and does not engage the

same until the arm 17 strikes the lever 28 to swing the stop arm upward and permit the pawl to engage the stud 24.

It will be understood that from this construction, when the key is first depressed the segment is locked at once and retained locked until the key becomes fully depressed. At this time the segment is released, and is not again locked during the retraction of 10 one of the keys until the final part of the return movement of the key.

Having thus described our invention, what we claim is:—

1. The combination of an operating member, an actuating member movable from a certain normal position to a certain fully advanced position, and a locking device normally free from the operating member, but arranged to be advanced at once on the 15 initial movement of the actuating member and brought to engage the operating member and prevent advance thereof from normal position, which locking member is retained in such locking position until the final 20 advance movement of the actuating member whereupon the locking member is shifted to release the operating member, and means for retaining the locking member out of locking 25 position during the entire return movement 30 of the said actuating member.

2. The combination of an operating member, an actuating member movable from a certain normal position to a certain fully advanced position, a lock arm arranged to 35 engage the operating member, a stop arm connected with the actuating member and normally holding the lock arm in a neutral position, said stop arm acting to release the lock arm to permit it to move to engaging 40 position at once upon advance of the actuating member, a lever connected with the lock arm and engaged by the said stop arm at the limit of its advance movement to swing the 45 lock arm away from said engaging position, and a pawl arranged to engage the lock arm

upon its said movement by the said lever whereby to hold the lock arm in neutral position, the said stop arm upon return of the actuating member to normal position serving to shift the pawl free from the lock arm 50 and also to reengage the lock arm to hold it in normal neutral position.

3. The combination of an operating member, an actuating member movable from a certain normal position to a certain fully advanced position, a stud on the operating member, a lock arm arranged to engage said stud, a spring on the lock arm to shift it to said stud engaging position, a stud on the lock arm, a stop arm connected with the actuating member and normally engaging the lock arm stud to hold the lock arm in neutral position out of range of the stud on the operating member, said stop arm on initial movement of the actuating member acting to free the lock arm to be swung by its spring to engage said operating member stud and lock the operating member, a lever connected with the lock arm and arranged to be engaged by the stop arm at the final portion of the advance movement of the stop arm whereby the lock arm is swung to shift it out of said engaging position with the operating member, a pawl arranged to engage the stud on the lock arm, a spring arranged to shift the pawl to said engaging position, and a stud on the pawl arranged to be engaged by the stop arm at the latter portion of its return stroke whereby the pawl is swung away from the stud on the lock arm, and the lock arm stud is thereupon engaged by the stop arm when returned to normal position to shift and retain the lock arm out of engaging position with the operating member, the lock arm spring being tensioned to overcome the tension of the said pawl spring.

WARREN FUHRMANN.
EDWARD M. SQUAREY.
